UNITED STATES PATENT OFFICE.

JOHN C. BROOKS, OF PATERSON, NEW JERSEY, ASSIGNOR TO CROMPTON & KNOWLES LOOM WORKS, OF WORCESTER, MASSACHUSETTS, A CORPORATION OF MASSACHUSETTS.

LOOM.

Application filed September 9, 1925. Serial No. 55,398.

My improvement relates to looms, such as plush looms, weaving two cloths, one above the other.

One object of my invention is to provide a loom of this type by which fabrics, such as print, cheese-cloth, duck, towelling and numerous other types of fabrics may be woven two pieces at a time one above the other thus doubling the efficiency of the loom.

10 Increased efficiency in weaving is often sought by using wide looms and then splitting the wide piece of cloth to form two lengths. This, however, is an objectionable method as there are no selvages on the split edges of the cloth.

Another object of my invention is to provide a novel loom which has two sheds with two stationary shuttle boxes on one end of the lay and a vertically-movable shuttle box 20 on the opposite end of the lay together with means for throwing shuttles simultaneously through the two sheds, the movable shuttle box being actuated so that after a shuttle has been discharged therefrom into one shed, 25 said box is shifted during the flight of the shuttles into position to receive the shuttle coming through the other shed.

In order to give an understanding of the invention I have illustrated in the drawings 30 a selected embodiment thereof which will now be described after which the novel features will be pointed out in the appended claims.

Fig. 1 is a front view of a loom embodying 35 my invention;

Fig. 2 is a right hand end view of the loom with a part broken out;

Fig. 3 is a rear view of the movable shuttle box detached from the loom;

40 Fig. 4 is a section on the line 4—4, Fig. 3;

Fig. 5 is a horizontal sectional view of the movable shuttle box.

In the drawings P indicates the frame of a loom, the latter having the lay L mounted 45 on the lay swords C which in turn are carried by the rock shaft B, and F indicates the reed carried by the lay and E the reed cap. G indicates the heddles, H indicates the filling fork grid, I the fork lever, and K 50 the cam for actuating the latter, said cam being mounted upon the cam shaft A. These parts, which are shown more or less diagrammatically in the drawings, are or may

be all as usual in looms and form no part of my present invention.

55 The loom is of that type in which the heddles are arranged to form two sheds, one above the other for the purpose of weaving either a double fabric or two fabrics at the same time.

60 The operating mechanism for the heddles is not shown herein as it forms no part of the present invention and may have any suitable construction adapted to form the two sheds one above the other.

65 One feature of the present invention relates to a construction embodying two shuttle boxes on one end of the lay, one for each of the two sheds, and a single movable shuttle box on the other end of the lay which is arranged to discharge its shuttle through one 70 shed and then to be moved to receive the shuttle coming through the other shed.

75 Mounted on one end of the lay are the two shuttle boxes 1 and 2 each provided with the usual binder 3. These shuttle boxes are stationary relative to each other and to the lay. On the other side of the lay is a movable shuttle box 21 which is movable vertically in suitable guides 23 rising from the lay.

80 Means are provided for throwing a shuttle from one of the stationary shuttle boxes 1, 2 through the corresponding shed and for simultaneously throwing a shuttle from the movable shuttle box 21 through the other 85 shed and then for shifting the shuttle box 21 into position to receive the incoming shuttle which has been thrown from the stationary shuttle box.

90 The shuttle box 21 which plays up and down in the space 20 between the guides 23 differs from a regular drop box in that it has an open space through its bottom through which to eject a spent filling carrier and further in that it has a hinged bottom to meet the requirements of changing its inner conformations when weaving double plush, as will be hereinafter mentioned.

95 This shuttle box 21 has in its rear face an opening 24 to receive the binder 25 and it is 100 supported on a vertical rod or bar 22 which is secured to the rear edge thereof, as shown in Fig. 4. The upright post or support 22 is guided by a bracket 29 fast on an extension of the rock shaft B and the shuttle 105 box is given its vertical shifting movement

by means of a cam 34 fast on the cam shaft A. For this purpose the lower end of the support 22 is pivotally connected with one end of a lever 30 which is pivoted on a rock shaft 31 supported by the loom frame and a suitable bracket or support 32, said lever 30 having a roll 33 thereon which is actuated by the cam 34. This cam 34 is so constructed that immediately after the shuttle has been thrown from the shuttle box 21 through one shed said shuttle box will be immediately shifted into position opposite the other shed to receive the shuttle which has been thrown from one of the stationary shuttle boxes.

Assuming that the lay is in its vertical position with a shuttle in the lower shuttle box 2 and also a shuttle in the movable shuttle box 21 and the latter in its lowered position then as the lay moves backwardly the cam 34 will raise the shuttle box 21 into position opposite the upper shed and as the lay passes the top center the two shuttles, one at the left hand side of the lay, Fig. 1 in the shuttle box 2, and the other at the right hand side of the lay in the raised shuttle box 21, will be simultaneously thrown across the lay, each shuttle traveling through its own shed. As soon as the shuttle has been thrown from the shuttle box 21 the cam 34 allows the shuttle box to drop into position shown in Fig. 1 wherein it will receive the shuttle coming through the lower shed and which has been thrown from the shuttle box 2. The shuttle which was thrown from the shuttle box 21 through the upper shed is received in the shuttle box 1. At the next pick the shuttle is thrown from the shuttle box 1 through the upper shed and simultaneously the shuttle in the shuttle box 21 is thrown therefrom through the lower shed and as soon as the shuttle has been discharged from the shuttle box 21 the latter is raised by the cam 34 into position to receive the shuttle coming through the upper shed. Thus the single shuttle box 21 at one end of the lay operates to receive shuttles coming through either shed and to throw the shuttles through both sheds.

Pneumatic mechanism is herein shown for operating the shuttles. Each shuttle 70 is provided at its end with a tip 71 which is formed with a vertical slot extending therethrough. Each tip is provided with a hollow shank 72, the bore 71 of which communicates with the vertical slot.

Each shuttle box has associated therewith an air delivery pipe through which air is discharged for blowing the shuttles across the shed, these pipes being indicated at 4, 5 and 35 respectively. These delivery jet pipes are so positioned that when the shuttle enters the box they will be projected into the bore 81 of the shuttle tip as shown in

Fig. 5. When the shuttle is boxed, therefore, the end of the corresponding jet tube enters the end of the bore 81 and forms approximately a closed space between the end of the jet tube and the inner end of the tube. 70

Means are provided for delivering a blast of air under pressure when the shuttles are to be thrown and the delivering of this air in said closed space results in efficiently and satisfactorily throwing the shuttle across 75 the shed.

The pipes 4 and 5 for the stationary shuttle boxes 1 and 2 lead to a header 8 which is connected by a pipe 9 to a source of compressed air supply. Each pipe 4 and 5 80 has a valve therein for controlling the discharge of fresh air through the jet pipe, these valves being indicated at 6 and 7 respectively. The valve 6 has an arm 10 by which it is actuated, said arm being connected by a link 12 to a lever 14 that in turn is pivotally mounted on a shaft or rod 16, said lever 14 being acted upon by a cam 18 fast on the cam shaft A. Similarly, the valve 7 is provided with an arm 11 which is connected by a link 13 to one end of a lever 15 also pivoted on the rod 16, said lever 15 being acted upon by a suitable cam 19 on the cam shaft A. 85

The jet pipe 35 is connected by a flexible pipe connection 35' of surplus length to a valve 36 which is supported by a bracket 37 on the end of the lay, the valve being supplied with compressed air through a pipe 38. The flexible pipe connection 35 permits 100 vertical movement of the shuttle box 21 without disrupting the air connections. 105

The valve 36 is provided with an arm 60 which is connected by a link 61 to a lever 62 pivoted on a supporting shaft 63, said lever having a roll 64 at its ends which engages and is acted on by a cam 65 fast on the cam shaft A. The cams 18, 19 and 65 are so designed and timed that the valves 7 and 36 will be operated in the proper sequence to 110 throw the shuttles across the sheds as above described.

The loom frame has a supporting bracket 39 secured to its front portion, which bracket carries a stud 40 on which is mounted the filling magazine M. This bracket also supports the transfer lever 42 by which the filling is transferred from the magazine to the shuttle, said lever being pivoted to the bracket 39 at 90. 115

44 indicates the feeler which is slidably mounted in a bearing or support 91 formed on the bracket and is provided with a pin 92 adapted to engage the upper end of an elbow lever 45 which is pivoted to the bracket 39 at 93. The horizontal arm of this elbow lever is connected by a link 48 to a push pawl or bunter 47, the latter being pivotally connected to the upper end of an elbow lever 46 that is pivoted at 94 to the 120

bracket 39. The horizontal end 49 of the lever 46 rests on and is actuated by a cam 50 fast on the cam shaft A. At each rotation of the cam shaft A, therefore, the elbow lever 46 will be vibrated and the bunter 47 will be correspondingly vibrated in a horizontal direction.

The filling replenishing lever 42 is actuated by a lever 43 which is pivoted to the bracket 39 at 95. This lever 43 in turn is given its operative movement at the proper time by a pusher or contact piece 56 which is mounted on a rod 55 that is slidably mounted in bearings 54 and 53 carried by the bracket 39 and the loom frame respectively. This rod 55 is normally held in its rearward position by means of a spring 57 which encircles one end of the rod and is confined between the bearing 53 and a collar 20 or pin 58 on the rod.

The feeler 44 co-operates with the shuttle which is in the movable shuttle box 21 and filling transfer is made while the shuttle is in said box 21. The feeler 44 thus co-operates alternately with the two shuttles, said feeler engaging the filling in one shuttle during one pick and the filling in the other shuttle during the next pick. So long as either shuttle contains a reasonable amount 30 of filling then on each forward beat of the lay the engagement of the feeler with the filling will force the feeler backwardly thereby operating through the lever 45 and link 48 to raise the bunter 47 above the contact piece or pusher 56. It will be remembered that the bunter 47 is being vibrated in a horizontal direction through the operation of the cam 50 but so long as there is filling in either shuttle said bunter will be raised 35 above the contact piece during its excursion to the left and, therefore, will not engage said contact piece, when, however, the filling in any shuttle becomes exhausted the feeler will not have the requisite movement when 40 the lay beats up to raise the bunter 47 above the contact piece 56 and said bunter will, therefore, engage the contact piece and as the bunter is moved toward the left by the cam 50 said bunter will engage the contact 45 piece 56 and move the latter also to the left. Such movement of the contact piece will bring it into engagement with the lever 43 thus swinging said lever to the left and as the upper end of the lever engages an arm 50 of the transfer lever 42 said transfer lever will be operated to transfer the bunter from the magazine to the shuttle. The spring 57 returns the parts to their normal position as 55 the lay moves back.

The lever 43 is provided with an arm 51 which engages a pin 52 carried by the feeler 44. By means of this construction whenever the arm 43 is moved to effect transfer of filling the feeler 44 will be withdrawn from 60 the path of the incoming bobbin so that

the feeler will not interfere in any way with the transfer.

The operation of the shuttle box 21 has been referred to above. Assuming that the shuttles are disposed as shown in Fig. 1, one shuttle being in the lower shuttle box 2 and the other in the other shuttle box 21 which is in its lowered position, and that the lay is in its forward position then as the lay moves backwardly the cam 34 will raise the shuttle box 21 into position to throw the shuttle through the upper shed and as the lay passes the top center the cam 19 will operate to open the valve 7 and cam 65 and will actuate its lever 62 to open the valve 36 with the result that the shuttle will be thrown from the shuttle box 2 through the lower shed and the other shuttle will be thrown simultaneously from the raised shuttle box 21 through the upper shed. As soon as the shuttle has been discharged from the shuttle box 21, said box will be dropped to its lowered position to receive the incoming shuttle from the left hand side of the loom which is travelling through the lower shed. At the next pick of the loom the shuttle box 21 maintains its lowest position until the shuttle therein has been thrown through the lower shed, the shuttle then in the upper shuttle box 1 having been simultaneously thrown through the upper shed. When the shuttle has been discharged from the lower box 21 the latter will rise to receive the upper shuttle travelling through the upper shed and will then be lowered to pass under the filling magazine, this movement being accomplished by the operation of the cam 34. At each beat up the shuttle box 21 is in its lowered position, in which position the shuttle therein is located correctly to be engaged by the feeler 44. Said shuttle box thus is placed in a predetermined position at each beat up and each shuttle is thus brought into position to receive new filling supply at alternate picks.

The usual filling fork motion H, I, K serves to stop the loom on total absence or breakage of the filling.

The above relates to the weaving of a double plush fabric in which the top shuttle is supported by the bottom warp threads of the top shed during its travel through the shed. For this purpose the outside shape of the top shuttle is formed to conform to the angle of the warp threads while shedding. To meet this condition the bottom 28 of the shuttle box 21 is pivoted as shown in Fig. 4 and when the shuttle box 21 is raised as above mentioned the bottom opens slightly as shown by dotted lines Fig. 4 to conform to the shape of the shuttle. The box bottom 28 is shown as pivoted to ears or projections 26, 27 at the ends of the box.

When weaving two distinct fabrics I provide a rigid bridge to support the running

top shuttle, said bridge being herein shown as a rail 90 which is secured to the lay.

Having described my invention so that it can be understood by those versed in the art, 5 I claim:

1. In a loom having two warp sheds, a lay, two superposed shuttle boxes on one end of the lay, a single shiftable shuttle box on the other end of the lay, means for throwing a shuttle from one of the two shuttle boxes through one warp shed, means for simultaneously throwing a shuttle from the single shuttle box through the other warp shed, and means to shift the single shuttle 10 box after the shuttle is thrown therefrom into position to receive the shuttle coming from the opposite end of the lay.
2. In a loom having two warp sheds, a lay, two shuttle boxes on one end of the lay, a single shiftable shuttle box on the other end of the lay, pneumatic means for throwing a shuttle from one of the two shuttle boxes through one warp shed and for simultaneously throwing a shuttle from the single 15 shiftable shuttle box through the other warp shed, and means to shift the single shiftable shuttle box after the shuttle has been thrown therefrom into position to receive the shuttle coming from the opposite end of the lay.
3. In a loom having two warp sheds, a vibrating lay, two shuttle boxes on one end of the lay stationarily mounted relative to each other, a single shiftable shuttle box on the other end of the lay, means for throwing a shuttle from one of the two shuttle boxes through one warp shed, means for simultaneously throwing a shuttle from the single shuttle box through the other warp shed, and means to shift the shiftable shuttle box 20 after the shuttle has been thrown therefrom into position to receive the shuttle coming from the opposite end of the lay and to place said shuttle box in a predetermined position at each beat-up of the lay.
4. In a loom having two warp sheds, a vibrating lay, two shuttle boxes on one end of the lay stationarily mounted relative to each other, a single shiftable shuttle box on the other end of the lay, means for throwing a shuttle from one of the two shuttle boxes through one warp shed, means for simultaneously throwing a shuttle from the single shuttle box through the other warp shed, and means to shift the shiftable shuttle box 25 after the shuttle has been thrown therefrom into position to receive the shuttle coming from the opposite end of the lay and to place said shuttle box in a predetermined position at each beat-up of the lay.
5. In a loom having two warp sheds, a vibrating lay, two shuttle boxes on one end of the lay stationarily mounted relative to each other, a single shiftable shuttle box on the other end of the lay, means for throwing a shuttle from one of the two shuttle boxes through one warp shed, means for simultaneously throwing a shuttle from the single shuttle box through the other warp shed, and means to shift the shiftable shuttle box 30 after the shuttle has been thrown therefrom into position to receive the shuttle coming from the opposite end of the lay and to place said shuttle box in a predetermined position at each beat-up of the lay.
6. In a loom having two warp sheds, a vibrating lay having on one end a single shiftable shuttle box, means for throwing said shuttle from said shuttle box through one shed and simultaneously throwing a shuttle from the opposite end of the lay through the other shed, means to shift said shiftable shuttle box after the shuttle has been thrown therefrom into position to receive the shuttle coming through the other shed and to place said shuttle box in a predetermined position upon each beat-up of the lay.
7. In a loom having two warp sheds, a vibrating lay having on one end a single shiftable shuttle box, means for throwing said shuttle from said shuttle box through one shed and simultaneously throwing a shuttle from the opposite end of the lay through the other shed, means to shift said shiftable shuttle box after the shuttle has been thrown therefrom into position to receive the shuttle coming through the other shed and to place said shuttle box in a predetermined position upon each beat-up of the lay, a feeler positioned to be engaged by the filling in the shuttle that is in said shiftable shuttle box at each beat-up of the lay, and filling-replenishing mechanism controlled as to its operation by said feeler.
8. In a weft replenishing loom, a lay, a plurality of shuttles, a shiftable shuttle box at one end of said lay, a magazine mounted at the end of the loom adjacent said shiftable shuttle box, means to bring said shiftable box to a predetermined vertical position relative to said magazine for weft replenishment as the lay approaches front center, and means to transfer a fresh weft carrier to a shuttle in said shiftable box.
9. In a weft replenishing loom, a lay, a plurality of shuttles, a plurality of superposed shuttle boxes at one end of the lay, a shiftable shuttle box at the opposite end of the lay, a weft replenishing magazine mounted at the end of the lay adjacent said shiftable shuttle box, a weft detecting mechanism effective to indicate substantial weft exhaustion in any one of said shuttles, means to move the shiftable shuttle box and the shuttle therein vertically on said lay to a 110
10. In a weft replenishing loom, a lay, a plurality of shuttles, a shiftable shuttle box at one end of the lay, a magazine mounted at the end of the loom adjacent said shiftable shuttle box, a weft detecting mechanism effective to indicate substantial weft exhaustion in any one of said shuttles, means to move the shiftable shuttle box and the shuttle therein vertically on said lay to a 115
11. In a weft replenishing loom, a lay, a plurality of shuttles, a shiftable shuttle box at one end of the lay, a magazine mounted at the end of the loom adjacent said shiftable shuttle box, a weft detecting mechanism effective to indicate substantial weft exhaustion in any one of said shuttles, means to move the shiftable shuttle box and the shuttle therein vertically on said lay to a 120
12. In a weft replenishing loom, a lay, a plurality of shuttles, a shiftable shuttle box at one end of the lay, a magazine mounted at the end of the loom adjacent said shiftable shuttle box, a weft detecting mechanism effective to indicate substantial weft exhaustion in any one of said shuttles, means to move the shiftable shuttle box and the shuttle therein vertically on said lay to a 125
13. In a weft replenishing loom, a lay, a plurality of shuttles, a shiftable shuttle box at one end of the lay, a magazine mounted at the end of the loom adjacent said shiftable shuttle box, a weft detecting mechanism effective to indicate substantial weft exhaustion in any one of said shuttles, means to move the shiftable shuttle box and the shuttle therein vertically on said lay to a 130

predetermined position for weft replenishment, and means to transfer a fresh weft carrier from said magazine to said substantially exhausted shuttle.

5 10. In a loom, a lay, a weft replenishing mechanism at one end thereof, a plurality of shuttles, means to receive a shuttle at different elevations on the weft replenishing end of said lay, and means to present each shuttle at the same predetermined vertical position for weft replenishment.

15 11. In a loom, a lay, a weft replenishing mechanism at one end thereof, a plurality of shuttles, means to receive a shuttle at different elevations on the weft replenishing end of said lay, and means to present each shuttle at the same predetermined vertical position for weft replenishment and to restore said shuttle to initial position between the arrival and departure of said shuttle at the weft replenishing end of said lay.

20 12. In a loom, a lay, a weft replenishing

mechanism at one end thereof, a plurality of shuttles, means to receive said shuttles at each end of the lay, and means to present 25 a shuttle at the weft replenishing end of said lay in a predetermined position for weft replenishment and to thereafter restore said shuttle to its initial position between the arrival and departure of said shuttle at the 30 weft replenishing end of the lay.

13. In a loom, a lay, a weft detecting mechanism at one end thereof, a plurality of shuttles, means to receive said shuttles at each end of the lay, and means to move a shuttle at the weft detecting end of said lay from initial position to a predetermined position for weft detection and to thereafter restore said shuttle to its initial position during a single oscillation of the lay and between the arrival and departure of said shuttle at the weft detecting end of the lay. 40

In testimony whereof I affix my signature.

JOHN C. BROOKS.
